CRADLE ADJUSTMENT FOR STRANDING MACHINES

David S. Robbins, Worcester, Mass., and Albert C. Uihlein, New Haven, Conn., assignors to The American Steel and Wire Company of New Jersey, a corporation of New Jersey

Application April 15, 1938, Serial No. 202,330

8 Claims. (Cl. 117—46)

This invention relates to stranding machines, and particularly to a means of adjusting the cradles of such machines.

In stranding machines of the planetary type as used for making wire rope and the like, there is provided a plurality of cradles, each holding a reel of wire, arranged concentrically about the axis of the machine with the axes of the cradles positioned parallel thereto. The cradles are rotated about the axis of the machine and, at the same time, about their own axes as the wire is reeled off to make the wire rope.

Heretofore, the cradles were keyed or otherwise securely attached to their supporting axes in set relationship to each other. While it is necessary in certain types of spinning to maintain the cradles in set parallel relationship, there are other types of spinning where a different relationship must be maintained and a different stranding machine would have to be provided for each type of spinning.

With the aid of the present invention, various types of wire rope spinning can be performed on the same machine, thereby eliminating the need of a machine for each particular type of spinning.

It is one of the objects of our invention to provide a stranding machine which will produce a wire rope of various types.

It is another object of the invention to provide an improved adjustable support for cradles of stranding machines.

It is a further object of the invention to provide a stranding machine in which the cradles can be adjusted to various positions relative to each other.

Various other objects and advantages of this invention will more fully appear during the course of the following specification and will be particularly pointed out in the appended claims.

In the accompanying drawings we have shown, for the purpose of illustration, one embodiment which our invention may assume in practice.

In these drawings:

Figure 1 is a plan of the cradle assembly of a planetary type wire stranding machine equipped with the improved cradle adjustment of our invention;

Figure 2 is a longitudinal section through the end of the cradle and our improved adjusting device;

Figure 3 is a section taken on line III—III of Figure 2;

Figure 4 is a section taken on line IV—IV of Figure 1;

Figure 5 is a view showing the face of the plate clutch on the sleeve; and

Figure 6 is a similar view, showing the face of the cooperating plate assembled on the cradle.

There is shown, in Figures 1 and 2 of the drawings, the cradle assembly of a conventional type stranding machine having a plurality of cradles 2 concentrically arranged about the main drive-shaft or axis 3 of the machine, each having a reel of wire 4 rotatably mounted therein. The cradles are rotatably mounted parallel to the axis of the machine between a pair of spiders 5 and 6, the spider 6 having gear teeth on the periphery thereof which engage with a pinion gear 7 positioned on a suitable drive-shaft 8 at the side of the machine. The cradles 2 are rotated by stud shafts 9 connected to one end thereof which are mounted in suitable bearings positioned in the spider 6. The stud shafts 9 have pinion gears 10 on the outer end thereof which are adapted to mesh with a gear 11 mounted on the main shaft 3 of the machine. There is also mounted on the main shaft 3 a gear 12 which is driven by a pinion gear 13 positioned on a suitable drive shaft 14 on the opposite side of the machine.

It will be understood, then, that as the main shaft 3 of the machine is rotated by means of gears 12 and 13 through the action of the drive-shaft 14, the group of cradles are also rotated by gears 6 and 7 through the action of the drive-shaft 8. At the same time, the cradles 2 are rotated about their axes, due to the cooperation between the pinion gears 10 and the gear 11. Such a cradle assembly and drive is conventional in most stranding machines of the planetary type and, of course, does not form any part of our invention.

According to the present invention, there is suitably mounted on the inner face of the yoke 40 of each of the cradles 2, preferably by means of cap-screws 15 or other suitable means, at the driven end of each of the cradles, a clutch-plate 16 having claws 17 or other suitable engaging means on the outer face thereof. There is mounted on each of the stud shafts 9 and slidably keyed thereto, a sleeve 18 having a groove 19 positioned at one end and around the periphery thereof and a clutch-plate 20, similar to the clutch-plate 16, suitably attached thereto and preferably made an integral part thereof, having notches 21 on the inner face thereof which are adapted to cooperate with the claws 17 of the clutch-plate 16. The ends of the shafts 9 are provided with a suitable threaded portion 22 and each has mounted there-

on preferably a castellated nut 23 having an annular extending portion 24 which is adapted to fit over and around the outer end of the sleeve 18. The annular portion 24 of the nuts carries 5 preferably a cap-screw 25 whose inner end is adapted to fit loosely in the slot 19 on the end of the stud shaft 9.

In order to adjust any cradle to a desired position, the nut 23 is turned in the loosening direction which, in turn, moves the sleeve 18 and the clutch-plate 20 to the left, as shown in Figure 2, disengaging the interengaging notches in the opposed faces of the two clutch-plates and thereby allowing free movement and adjustment of 10 the cradle. After the cradle is adjusted to the desired position, the nut 23 is then, of course, turned in the tightening direction, moving the sleeve 18, together with the clutch-plate 20, to the right and bringing the notches 17 and 21 of 15 the two plates into engagement, locking the cradle to the shaft 9. The nut 23 is held in this position preferably by means of a suitable pin 26 passing through the end of the nut and the stud shaft 9.

25 As a result of the present invention, it will be seen that cradles of stranding machines equipped with the simple and inexpensive device of our invention, can be quickly and easily adjusted to any desired position relative to one another. 30 That is to say, any single cradle may be rotated and set in any desired position relative to the other cradles, thereby eliminating the need of a plurality of different types stranding machine for the spinning of different types of wire rope.

35 While we have, in this application, specifically shown and described an embodiment of our invention, it will be understood that this embodiment is merely for the purpose of illustration and description, and that various other forms may be 40 devised within the scope of the invention, as defined in the appended claims.

We claim:

1. In combination with a wire stranding machine of the planetary type having a plurality of 45 cradles concentrically arranged therein, each of said cradles having a shaft for driving the same, means for adjusting each of said cradles in a plurality of positions relative to each of their respective shafts.

50 2. In combination with a wire stranding machine of the planetary type having a plurality of cradles concentrically arranged therein, each of said cradles having a shaft for driving the same, means carried by each of said cradles which is 55 adapted to cooperate with means carried by each of their respective shafts to adjustably position the same therewith in a plurality of positions.

3. In combination with a wire stranding machine of the planetary type having a plurality of 60 cradles concentrically arranged therein, each of said cradles having a shaft for driving the same, means for adjusting the position of each of said cradles relative to their respective shafts, including a movable collar carried by each of said shafts 65 and slidably keyed thereto, and means carried by said collars which is adapted to cooperate with means carried by said cradle to lock the same therewith in a plurality of positions.

4. In combination with a wire stranding machine of the planetary type having a plurality of cradles concentrically arranged therein, each of 5 said cradles having a shaft for driving the same, means for adjusting the position of each of said cradles relative to their respective shafts, including a movable collar carried by each of said shafts and slidably keyed thereto, and a clutch-plate carried by each of said collars which is 10 adapted to cooperate with means carried by said cradle to lock the same therewith in a plurality of positions.

5. In combination with a wire stranding machine of the planetary type having a plurality of cradles concentrically arranged therein, each of 15 said cradles having a shaft for driving the same, means for adjusting the position of each of said cradles relative to their respective shafts, including a movable collar carried by each of said shafts and slidably keyed thereto, and a clutch-plate 20 carried by each of said collars which is adapted to cooperate with a similar clutch-plate carried by said cradles to lock the same therewith in a plurality of positions.

6. In combination with a wire stranding machine of the planetary type having a plurality of 25 cradles concentrically arranged therein, each of said cradles having a shaft for driving the same, means for adjusting the position of each of said cradles relative to their respective shafts, including a movable collar carried by each of said shafts and slidably keyed thereto, and a clutch-plate 30 carried by each of said collars, said clutch-plates having interengaging means on one face thereof which is adapted to interengage with means carried by the opposed face of a similar clutch-plate carried by said cradles to lock the same therewith in a plurality of positions.

7. In combination with a wire stranding machine of the planetary type having a plurality of 40 cradles concentrically arranged therein, each of said cradles having a shaft for driving the same, means for adjusting the position of each of said cradles relative to their respective shafts, including means carried by each of said shafts which is 45 slidably engaged therewith, said means adapted to cooperate with means carried by said cradles to lock the same therewith in a plurality of positions.

8. In combination with a wire stranding machine of the planetary type having a plurality of 50 cradles concentrically arranged therein, each of said cradles having a shaft for driving the same, means for adjusting the position of each of said cradles in a plurality of positions relative to their 55 respective shafts including a movable collar carried by each of said shafts and slidably keyed thereto, a clutch-plate carried by each of said collars, said clutch-plates having interengaging means on one face thereof which is adapted to 60 interengage with means carried by the opposed faces of similar clutch-plates carried by said cradles and means for holding the interengaging means of said plates in engagement with each other.

65 DAVID S. ROBBINS.
ALBERT C. UIHLEIN.
